HOUSING FOR A SEWAGE PUMP STATION OR THE LIKE

Simpson V. Prator, Mineral Wells, Tex., assignor to Texas
Vitrified Pipe Company, Mineral Wells, Tex., a corpo-
ration of Texas

Filed Aug. 6, 1959, Ser. No. 57,083

Term of patent 14 years

(Cl. D13—1)

FIG. III

FIG. IV

FIG. II

FIG. I is a perspective view of the housing for a sewage pump station or the like showing my new design;
FIGURE II is a side elevational view thereof;
FIGURE III is a top plan view thereof; and
FIGURE IV is an elevation thereof as seen from the right of FIG. II.

I claim:

The ornamental design for a sewage pump station or the like, substantially as shown.
